UNITED STATES PATENT OFFICE.

EDWARD M. ZIER AND MICHAEL ZIER, OF NEW ALBANY, INDIANA.

ENGINE.

Application filed October 21, 1922. Serial No. 595,965.

Our invention relates to new and useful improvements in an internal combustion engine of the four cycle type and has for its principal object the provision of an engine 5 having a compressing cylinder and piston interposed between two firing cylinders and pistons, said compressing piston upon each downward stroke drawing in a charge of gas and upon each upward stroke forcing said 10 charge into one or the other of the firing cylinders.

Another object consists in forming the compressing cylinder and piston of a greater diameter than the firing cylinders and pistons 15 tons and so connecting the pistons to a common drive shaft that the firing pistons will operate in advance of the compressing piston, the compressing cylinder and piston being of greater diameter than the firing 20 cylinders allowing the gases to be compactly compressed in the firing cylinders allowing a greater combustion than would be the case if not so compactly compressed and the firing pistons operated in advance of the compressing 25 piston allowing the connection between the piston rods and crank shaft to be off center when the firing takes place.

A further object resides in positioning the valves in a novel manner and providing a 30 passage from the compression cylinder to each of the firing cylinders, a valve normally closing each passage but adapted to be opened for drawing in and compressing a charge and one valve being closed while the 35 other is open.

With the above and other objects in view our invention consists in the novel details of construction and combination of parts described in the following specification and 40 illustrated in the accompanying drawings in which:—

Fig. 1 is a fragmental longitudinal vertical section through the cylinder casting and cover with the pistons, piston rods, crank 45 shaft and spark plugs shown in elevation.

Fig. 2 is a fragmental horizontal section through the cylinder casting cover with the cylinder casting and valves shown in top plan.

Fig. 3 is a transverse vertical section through the cylinder casting, cover, and crank case, with parts shown in elevation, and

Fig. 4 is a fragmental longitudinal vertical section through the cylinder casting and

cover showing the valves and valve operating mechanism in side elevation.

In the drawings 1 indicates a portion of the cylinder casting formed with the firing cylinders 2 and 3 and the compressing cylinder 4 therebetween, pistons 5 and 6 operating in the cylinders 2 and 3, respectively, and piston 7 operating in the cylinder 4, the compressing cylinder 4 and its piston 7 being of greater diameter than the firing cylinders 5 and pistons for a purpose which will be later described. The casting 1 is formed with 60 openings or passages 8 surrounding the cylinders to receive the usual water or other cooling medium. While we have illustrated only a portion of the casting disclosing two firing cylinders and pistons and one compression cylinder and piston it will be understood that any number of cylinders and associated pistons may be provided, four 65 firing cylinders and pistons and two compressing cylinders and pistons being provided for an engine of the usual four cylinder type.

Supported on and secured to the top of the 70 casting 1 is the head 9 which separates the cylinders at the top, as shown, and is provided with the passages 10 for receiving the cooling medium. A spark plug 11 is carried by the head over each of the firing cylinders and these plugs will be connected to the usual ignition system for supplying the spark. The casting 1 is supported on the crank case 12, the crank case rotatably supporting the crank shaft 13 which extends 75 longitudinally beneath the casting. A piston rod 14 is connected at one end to the piston 5 and at the opposite end to the shaft 13, a piston rod 15 connects the piston 6 and shaft 13 and a piston rod 16 connects the 80 piston 7 with the crank shaft. The piston rods are so connected to the crank shaft that the firing pistons 5 and 6 will operate slightly in advance of the compressing piston 7.

Formed in the casting 1, adjacent the cylinder 2, is the intake port 17 and the exhaust port 18, the upper ends of these ports being formed with seats to receive the valves 19 and 20, respectively, which have the usual stems 21. Springs 22 surround these stems between the under side of the casting 1 and the washers 23 and normally hold the valves upon their seats. Formed in the casting 1, 85 adjacent the cylinder 3, is the intake port 24 105 and the exhaust port 25, the upper ends of these ports being formed with seats to receive the valves 26 and 27, respectively, which have the usual stems 28. Springs 29 surround these stems between the under side of the casting 1 and the washers 30 and normally hold the valves upon their seats. Formed in the casting 1, 110 adjacent the cylinder 4, is the intake port 31 and the exhaust port 32, the upper ends of these ports being formed with seats to receive the valves 33 and 34, respectively, which have the usual stems 35. Springs 36 surround these stems between the under side of the casting 1 and the washers 37 and normally hold the valves upon their seats.

and the exhaust port 25, the upper ends of the ports being formed with seats adapted to receive the valves 26 and 27 respectively which have the usual stems 28.

5 Springs 29 surround the stems between the underside of the casting and the washers 30 to normally hold the valves upon their seats. Openings 31 and 32 extend downwardly from the top of the casting 1, one 10 opening being on each side of the compressing cylinder 4, the opening 31 communicating with a passage 33 which leads to the firing cylinder 2 and the opening 32 communicating with a passage 34 which leads to 15 the firing cylinder 3. The opening 31 is formed at the upper edge with a seat to receive the valve 35 and the opening 32 is formed at the upper edge with a seat to receive the valve 36. The valves 35 and 20 36 have the usual stems 37 which are surrounded by the springs 38 between the under side of the casting 1 and the washers 39, the springs normally holding the valves upon their seats. Each of the valves 19, 25 20, 26, 27, 35 and 36 are adapted to be operated through means of the cams 40 on the cam shaft 41, said cams engaging the members 42 which in turn engage the ends of the valve stems. The cams will be so positioned as to properly time the opening of 30 the valves.

The inlet ports 17 and 24 are connected to the usual intake manifold and the exhaust ports 18 and 25 are connected to the usual exhaust manifold.

Having now described the detail construction we will describe more fully the operation. With the pistons in the position shown in Fig. 1 the valves 26, 27 and 36 40 are closed and the compressed gases in the firing cylinder 3 is ready to be fired, it being noted that the connection between the rod 15 and crank shaft 13 is off center. The piston 5 in the firing cylinder 2 has 45 reached about mid-way position and has drawn in gas through the inlet port 17, the valve 19 being open. When the firing takes place in the cylinder 3 the pistons 5, 6 and 7 will all continue their downward stroke, 50 the piston 5 drawing in gas through the port 17 and the piston 7 drawing in gas through the passage 33, from the cylinder 2, the valve 35 being open at the time of the firing. As shown and described the firing pistons 5 and 6 operate in advance of 55 the compressing piston 7 and the firing pistons 5 and 6 reach their lowermost positions and start on the up stroke while the piston 7 is still going down drawing in gas. 60 As the piston 5 moves up it compresses the gas which is has drawn into the cylinder 2 and when the piston 7 moves up it compresses the gas which has been drawn into the cylinder 4 and forces it through the 65 passage 33 into the cylinder 2. When the

piston 7 starts upwards the intake valve 19 will close but the valve 35 will remain open until the piston reaches its uppermost position when it will close. When the piston 6 starts up, the firing in the cylinder 3 70 having been accomplished, the exhaust valve 27 will open and the movement of the piston upwardly forces out the exhaust gases. The piston 5 will start on its second down stroke before the piston 7 reaches its uppermost position and will reach about mid-way position before the firing takes place. The cylinder 4 and piston 7 being of greater diameter than the cylinder 2 and piston 5 will tightly compress the gases 75 in the cylinder 2 to cause a greater explosion than takes place in engines of the usual construction and the connection of the rod 14 with the shaft 13 will be off center. When the piston 6 reaches its uppermost 80 position the intake valve 26 will be open and the exhaust valve 27 closed so that when the piston starts down gas will be again drawn into the cylinder 3. When the piston 7 again starts down gas will be drawn into the cylinder 4 through the passage 34, the valve 36 being open at the time the piston 7 starts down. On its up stroke the piston 6 will compress the gases in the cylinder 3 and the piston 7 on its up stroke will compress the gasses in the cylinder 4 and force it over into the cylinder 3 through the passage 34. It will be understood that when piston 7 starts up the intake valve 24 will be closed and the valve 36 will be closed when the piston 7 reaches its uppermost position. As the piston 5 goes up, while the piston 6 is compressing, it is exhausting the gas from the cylinder 2 through the exhaust port 18, the exhaust valve 20 being then opened. From the above it will be seen that the piston 7 draws in gas on each down stroke and compresses it on each up stroke, delivering the compressed gases alternately to the cylinders 2 and 3, the greater diameter of the compressing cylinder and piston causing a tight compression of the gases in the firing cylinders. 105

The engine described may be made in the vertical, horizontal or V-shaped type and the compressing cylinder may be made any size or different in stroke from the firing cylinder to regular the amount of gas compressed. Each cylinder fires each time the crank shaft turns over twice. 115

Having fully described our invention what we claim and desire to secure by Letters Patent is:

1. An engine comprising a pair of firing cylinders, a compressing cylinder interposed between the firing cylinders, a piston operable in each of the cylinders, means for simultaneously drawing a charge into one of the firing cylinders and the compressing cylinder upon the downward stroke of the 125

pistons therein, and means for compressing the charge in both of the cylinders upon the upward movement of the pistons therein and transferring the compressed charge 5 from the compressing cylinder into the firing cylinder.

2. An engine comprising a pair of firing cylinders, a compressing cylinder, pistons operable in each of the cylinders, means for 10 drawing a charge into one of the firing cylinders and compressing cylinder while the firing is taking place in the other firing cylinder, and means for compressing the charge in said first mentioned cylinders while 15 exhausting the gases from the last mentioned cylinder.

3. An engine comprising a pair of firing cylinders, a compressing cylinder, a piston operable in each of the cylinders, valved 20 passages leading from the compression cylinder to each of the firing cylinders, and means for opening the valve in one of the 25 passages during the downward movement of the pistons so that a charge will be drawn into one of the firing cylinders and the compressing cylinder while the valve in the 30 other passage remains closed.

4. An engine comprising a pair of firing cylinders, each having an intake and an exhaust port, a valve in each of the intake and exhaust ports, a compressing cylinder, a valved passage leading from the compressing cylinder to each of the firing cylinders, pistons operable in each of the cylinders, 35 and means for operating the valves in the intake and exhaust ports and the passages between the cylinders so that when firing is taking place in one of the firing cylinders a charge will be drawn into the other firing 40 cylinder and compressing cylinder upon the downward movement of the pistons therein and when the exhaust gases are being discharged from that cylinder which has fired

the charge in the other firing cylinder and compressing cylinder will be compressed 45 and the charge from the compressing cylinder will be transferred to that firing cylinder which has drawn in a charge.

5. An engine comprising a fire cylinder, a compressing cylinder, a piston operable in 50 each of the cylinders, the piston in the firing cylinder operating in advance of the piston in the compressing cylinder, and means whereby a charge is drawn into the firing and compressing cylinders upon the 55 down stroke of the pistons therein and compressed on the up stroke of the pistons, the firing piston operating in advance of the compressing piston allowing the compressing piston to continue to draw in the charge 60 after the firing piston has started on the up stroke and to continue its compressing after the piston in the firing cylinder has started on its firing stroke.

6. An engine comprising a pair of firing cylinders, a compressing cylinder, pistons operable in each of the cylinders, a valved inlet port and a valved exhaust port for each of the firing cylinders, a valved passage from each of the firing cylinders to the 65 compressing cylinder, and means for controlling the inlet and exhaust valves and the valves of the passages from the firing cylinders to the compressing cylinder so that on the down stroke of the pistons a charge 70 will be drawn into one of the firing cylinders and the compressing cylinder while a charge is firing in the other firing cylinder, the charge into the compressing cylinder being drawn from the firing cylinder through 75 the communicating passage.

In testimony whereof we hereunto affix our signatures.
